UNITED STATES PATENT OFFICE.

SAMUEL MAY, OF TORONTO, ONTARIO, CANADA.

BILLIARD-CUSHION.

SPECIFICATION forming part of Letters Patent No. 283,129, dated August 14, 1883.

Application filed May 25, 1883. (No model.)

To all whom it may concern:

Be it known that I, SAMUEL MAY, of Toronto, in the Province of Ontario, and Dominion of Canada, have invented a new and useful Improvement in Billiard-Cushions, of which the following is a full, clear, and exact description.

In the Letters Patent granted to me October 19, 1880, a metallic ribbon is shown embedded within an elastic rubber cushion for the purpose of giving greater and equal elasticity to the cushion at all points. The patent aforementioned contemplates the use of a tempered steel ribbon; but I have found by practice that the thin steel cannot be properly tempered and at the same time kept flat and straight, so that after tempering, in order to fit it for use in the cushion, the plates have to be hammered by a slow and expensive process.

My present invention has the object to avoid this expense and trouble connected with the use of the steel ribbon; and it consists in the use of thin brass, which is roll-tempered in sheets to the proper temper and thickness, and then cut into straight ribbons of the desired width by special machinery.

In the accompanying drawing I have shown a vertical sectional elevation of a portion of the billiard-table and cushion with the elastic ribbon applied thereto.

A is the cushion-rail. B is the bed of the billiard-table. C is the cushion-socket. D is the elastic-rubber portion of the cushion, and E is the hard-rubber portion thereof. F is the tempered-brass ribbon, having its lower

portion fitted in a socket, a, in the hard rubber E and its upper edge extending nearly to the upper face of the portion D of the cushion, the upper edge of the ribbon being at a point above where the ball G comes in contact with the cushion, as shown. The playing edge or nosing I of the cushion is set somewhat lower than the edge of sharp-edged cushions, so that the ball impinges at a point nearer its center, which insures certain advantages in the use of the table. The hard-rubber portion E of the cushion and socket a serve to hold the lower edges of the brass ribbon firmly, so that no end tension is required.

By using roll-tempered brass, as described above, I am able to produce a superior cushion for billiard-tables at a much less expense than when the ribbon is made of steel, as fire-tempered springs cannot be produced straight, and, besides, are not best suited for the purpose.

In place of using a socket-piece of hard rubber for the ribbon, a piece of canvas may be vulcanized in the soft rubber to form a socket.

Having thus described my invention, I claim as new and desire to secure by Letters Patent—

In billiard-cushions, the embedded metallic ribbon F, formed of roll-tempered brass, substantially as specified.

SAMUEL MAY.
